SNOWPLOW

Joseph Wandscheer, Sioux Center, Iowa

Application February 4, 1943, Serial No. 474,634

7 Claims. (Cl. 37—43)

My invention relates to a snow plow.

An object of my invention is to provide a snow plow with a combination of members so arranged as to cut the snow by means of radially disposed cutting bars of a special shape which will efficiently cut the snow ahead of further other members.

A further object of my invention is to provide, in combination with said cutting bars, a helical boring member to transfer the snow rearwardly.

A further object of my invention is to provide a pair of opposed helical conveyors mounted on the plow and transversely across the road bed which will convey the snow inwardly toward the center of the plow, and to provide a reversible fan arrangement which will blow the snow to either side of the roadway as desired.

A further and important object of my invention is to provide a helical conveyor having a spiral flange attached to or integral with the conveyor, which flange includes inwardly directed cutting and conveying edges for more efficiently cutting the snow and directing the same towards the shaft of the conveyor.

A further object of my invention is to provide such a flange member having a cutting edge either in a complete unit form on the helical conveyor or in detachable sections as desired.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a sectional side elevation taken substantially along the lines 1—1 of Fig. 2,

Figure 2 is a forward elevation of the plow.

Figure 3 is a sectional view taken along the lines 3—3 of Fig. 1,

Figure 4 is a section taken along the lines 4—4 of Fig. 1,

Figure 5 is a detail of the auxiliary cutting flange taken substantially along the lines 5—5 of Fig. 2,

Figure 6 is a modified form of the flange, and

Figure 7 is a further modified form showing the integral formation of the flange.

My invention contemplates a snow plow for cutting away snow gathered on a roadway, thence rearwardly, conveying the same into suitable means for deflecting the pulverized snow outwardly adjacent to the roadway. My invention also contemplates a special cutting flange attached to certain helical portions of the plow to enhance

the cutting and gathering effect of the helical conveyor.

I have used the character 10 to designate the hood of a truck or such vehicle upon which the plow is to be mounted, and with the forward wheels of the same indicated by the character 11. Firmly secured to the forward portions of the vehicle are the braces 12 which are attached at 13 to the side brackets 14 which brackets are attached to the rear wall 15 of the fan casing of the unit. The forward wall of the same casing is indicated by the character 16 and includes the portion 17 to which is attached the journal 18, and received within the journal 18 is the substantially horizontal shaft 19 which shaft, however, is pitched at a slight angle from the horizontal and which continues into the further forward portion 20.

Attached to the forward portion 20 is a hub portion 21, and secured to the hub portion 21 are a series of four helically pitched blades 22 which terminate in the forward edges 23 and extend rearwardly toward the left as viewed from Fig. 2. Attached to the forward end of the member 21 is the nose 25a, and attached at 24 to each member 22 and at the forward edge thereof are the cutting blades 25 which blades are pitched at the same angle from the forward motion as the members 22.

To strengthen the cutting blades 25 I provide the rear ribs 26 which extend substantially the entire distance in order to strengthen the blades along the entire length thereof. All of the blades 25 include arcuate forward cutting edges 27 positioned in the direction of rotation of the blades 25, which direction of rotation is in the direction of the arrow 28. The outer extremities of the blades 25 include a more pronounced arcuate portion 29 to increase the cutting effect and the blades terminate at the points 30.

The forward wall 16 of the fan casing merges with the side walls 31 which extends forwardly to the termination at 32, and attached between the side walls 31 is a deflector shield 33 having the side portions 34. Journalled within the bearings 35 which are attached to the side members 31 is a horizontally positioned transverse shaft 36 upon which is mounted the hub portion 37, and secured to the hub shaft 37 are the helical members 38 and 39. The left-hand helical member, as viewed from Fig. 2, is adapted to rotate toward the observer from the upper side, as is the helical member 39. However, these members are pitched oppositely to each other and so that they will convey the snow toward the center of the plow and toward the center of the opening 40, which opening

communicates with the fan housing. The right-hand end of the shaft member 37 extends through the side wall 31 and is attached to a suitable sprocket at 41 over which passes the chain drive 42 which engages an upper sprocket 43 which is attached to the horizontal shaft 44 which shaft is journaled in bearings 45 attached to the wall 16.

The shaft 44 is attached to a bevel gear 46 which bevel gear 46 meshes with a further bevel gear 47 (see Fig. 1) which is attached to the shaft 19. A casing (see Fig. 2) 48 encloses the chain drive 42. The opening 40 which communicates with the fan housing includes the enlarged portion at 49. Each of the helical conveyors 38 and 39 include formed therewith the partially arcuate cutting flanges 50 which flanges extend at a substantial angle from the plane of the helical conveyors 38 and 39 and which terminate in the sharp edges 51 which members 50 are later described more fully and are shown more clearly in Figs. 5, 6, and 7. It will be noted that these members extend forwardly corresponding to the turning motion of the helical conveyors.

Enclosing the shaft 19 and mounted concentric thereto is a further hollow cylindrical shaft 52 to which is attached the hub 53 to which are attached the spokes 54 which spokes are attached at 55 to the fan blades 56. The rear end of the shaft 19 is journaled within the casing 57 at 58 and is keyed to the large gear 59, and the forward portion of the hollow shaft 52 is journaled at 60 within the forward portion of the casing 57, and attached to the member 52 is the elongated key 61 upon which is slidably mounted the gear member 62 which gear member includes an annular portion 63 which engages the end 64 of a control rod 65 which rod 65 passes through the casing 57 and is attached at 66 to the control member 67 which, in turn, passes to the control cab of the vehicle.

A further shaft 68 is journaled at 69 within the casing 57 and is connected by means of the universal joint 70 to the power drive shaft 71 of the vehicle. Keyed to the shaft 68 is a gear 72 as well as a further forward gear 73 which gear 73 meshes with a further much thicker gear 74 which gear 74 rotates upon the shaft 75 (see Fig. 4). A further gear 76 is keyed to the forward end of the shaft 68. The fan casing itself, which is cylindrical in shape, is indicated generally by the character 77.

Received between the upper edges of the fan casing are a pair of side walls 78 having the configuration as shown substantially in Fig. 3 through which walls extend the shaft 79 which shaft 79 is attached to a suitable hydraulic or other motor 80 which is controlled by means of the pipe line 81 from the vehicle, which pipe line will include the oil for operating the motor 80. Attached to the shaft 79 is a deflector plate 82. Also attached to the members 78 are extending ears which ears are received within the channels 83 so that the members 78 can be slidably positioned at any desired point. Also merging with the members 78 is an arcuate plate 84 including an opening at 85, and attached at 86 to one of the members 78 is the rod 87 which includes a piston attached thereto and slidably engaged within the cylinder 88 which is pivoted at 89 to the bracket 90 which is attached at 91 to the sides of the casing 77.

The forward cutting flanges 50 which include the edges 51 are attached, as shown in Figs. 5 and 6, to the helical conveyors 38 and 39, either as an integral portion thereof, as shown in Fig. 7, or as separately bolted units as shown in Figs. 5

and 6. For instance, in Fig. 6, as shown, the sections can be separated at a line 92, thereby providing a series of sections which can be bolted about the entire helical periphery of the conveyors. As shown in Fig. 6, suitable openings are provided at 93 which receive the flat head screws 94 which pass through the openings in the flange 95, which flange 95 is substantially similar in all respects to the flange 50 except that it is a separate piece being attached to the member 38 by means of the nut 96 and includes a shoulder 97 for firm engagement with the helical conveyor. In this form of structure a portion of the member 95 is behind the conveyor, the direction of travel of the conveyor being indicated by the character 98.

Figure 5 illustrates a further modification, wherein a similar member 95 includes the forward cutting edge 51 and a shoulder 99 with a further portion 100 being snugly engaged against the forward face of the helical conveyor and with the machine screw 94 passing through a suitable opening 93 and being bolted by means of the screw 96 with a counter-sunk opening at 101 receiving the head of the machine screw. It should be specifically noted in all of these structures that the cutting edge 51 is positioned forwardly toward the direction of movement of the conveyor, and it will be understood that it can be made either in detached form as shown in Figs. 5 and 6, or in the integral form as shown in Figs. 2 and 7.

Now that the structure of my plow has been explained, I shall explain the operation thereof. As the plow travels forwardly, the cutting blades 25 are always driven in the direction of the arrow 28, and the cutting edges 27 and 29 have a tendency of cutting down the snow ahead of the other members with the pronounced arcuate portions 29 increasing this effect. The snow is then conveyed rearwardly by means of the helical flaps 22 and over the further helical member 38 and 39 which convey the snow toward the center of the plow and into the fan casing 77. Since the inwardly turned edges 51 are toward the direction of travel of the helical members, these members will tend to efficiently cut out that portion of the snow in the lower corners at 102 of the arrangement and will also materially assist in slicing inwardly as the snow is conveyed inwardly, thereby providing a positive attack on the snow in the desired direction. Also, since these members are inclined inwardly, they will provide the effect of inwardly directing the snow with respect to the shaft 37 as well as the center of the fan casing, which combined effect will efficiently and uniformly carry the snow in the desired manner toward the center of the fan housing.

The inclination of the blades 25 will also assist in the rearwardly conveying action, so that as a composite result, the operation of all of the units will provide the desirable effect of carrying or conveying practically all of the snow to the desired point in the best manner. The snow can be thrown to either side of the casing or plow as desired by means of the reversible arrangement which comprises principally the rod 65, which rod, when forced forwardly, will cause engagement of the gear 62 with the gear 76 which will cause one direction of rotation of the fan blades 56, and to reverse the fan, the rod 65 is drawn rearwardly through the agency of the rod 67, which causes the gear 62 to mesh with the gear 74, which gear 74 is constantly meshed with the gear 73. This, as will be seen from Fig. 4 and Fig. 1,

will reverse the direction of rotation of the fan blades.

Corresponding to the direction of rotation of the fan blades, the members 78 can be forced to the left or the right, as observed from Fig. 3 by means of a suitable hydraulic control, to the cylinder 88, which acts upon the rod 87 to carry the members 78 in either direction which, in turn, causes the opening 85 to be larger toward the left or the right. The hydraulic motor 80 can also be operated then to bring the plate 82 in whichever position is desired corresponding to the upper edges 103 of the members 78 so that the snow will be deflected to either side as desired and corresponding to the direction of rotation of the fan blades, Fig. 3 illustrating how the structure is arranged when the snow is thrown toward the left with the opening 85, however, still being in its central position just before being thrust toward the left. The shaft 44, through the engagement of the bevel gears, insures a uniform and constant drive in one direction of the helical conveyors 38 and 39.

It will now be seen that my invention provides all of the advantages mentioned heretofore in the objects of my invention, as well as other advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A snow plow comprising a cutting member including a substantially horizontal forwardly extending rotating shaft, a plurality of helically pitched blades attached to said shaft for rotation with the shaft, a plurality of cutting blades attached to and extending outwardly from the forward ends of said helically pitched blades, a fan casing, a fan rotatably mounted in said casing, and means for driving said fan and said cutting blades.

2. A snow plow comprising a cutting member including a substantially horizontal forwardly extending rotating shaft, a plurality of helically pitched blades attached to said shaft for rotation with the shaft, a plurality of cutting blades attached to and extending outwardly from the forward ends of said helically pitched blades, a fan casing, a fan rotatably mounted in said casing, and means for driving said fan and said cutting blades, said cutting blades including forward cutting edges of pronounced curvature at the ends thereof.

3. A snow plow comprising a cutting member including a substantially horizontal forwardly extending rotating shaft, a plurality of helically pitched blades attached to said shaft for rotation with the shaft, a plurality of cutting blades attached to and extending outwardly from the forward ends of said helically pitched blades, a fan casing, a fan rotatably mounted in said casing, means for driving said fan and said cutting blades, said cutting blades including forward cutting edges of pronounced curvature at the ends thereof, and helical conveyors positioned transversely across said plow and positioned directly behind said cutting blades and below said helically pitched blades.

4. A snow plow comprising a cutting member including a substantially horizontal forwardly extending rotating shaft, a plurality of helically

pitched blades attached to said shaft for rotation with the shaft, a plurality of cutting blades attached to and extending outwardly from the forward ends of said helically pitched blades, a fan casing, a fan rotatably mounted in said casing, means for driving said fan and said cutting blades, said cutting blades including forward cutting edges of pronounced curvature at the ends thereof, and helical conveyors positioned transversely across said plow and positioned directly behind said cutting blades and below said helically pitched blades, said transverse helical conveyors including a pair of oppositely pitched conveyors, said conveyors being pitched to convey snow toward the center of said plow, and said helical conveyors including flanges along the spiral extremities thereof, said flanges including edges directed inwardly toward the center of said plow, and in the conveying direction of said helical conveyors.

5. A snow plow comprising a cutting member including a substantially horizontal forwardly extending rotating shaft, a plurality of helically pitched blades attached to said shaft for rotation with the shaft, a plurality of cutting blades attached to and extending outwardly from the forward ends of said helically pitched blades, a fan casing, a fan rotatably mounted in said casing, means for driving said fan and said cutting blades, said cutting blades including forward cutting edges of pronounced curvature at the ends thereof, helical conveyors positioned transversely across said plow and positioned directly behind said cutting blades and below said helically pitched blades, said transverse helical conveyors including a pair of oppositely pitched conveyors, said conveyors being pitched to convey snow toward the center of said plow, and said helical conveyors including flanges along the spiral extremities thereof, said flanges including edges directed inwardly toward the center of said plow, and in the conveying direction of said helical conveyors, and means for reversing said fan to provide means for throwing snow to either desired side of said snow plow.

6. A snow plow comprising a cutting member including a substantially horizontal forwardly extending rotating shaft, a plurality of helically pitched blades attached to said shaft for rotation with the shaft, a plurality of cutting blades attached to and extending outwardly from the forward ends of said helically pitched blades, a fan casing, a fan rotatably mounted in said casing, means for driving said fan and said cutting blades, said cutting blades including forward cutting edges of pronounced curvature at the ends thereof, helical conveyors positioned transversely across said plow and positioned directly behind said cutting blades and below said helically pitched blades, said transverse helical conveyors including a pair of oppositely pitched conveyors, said conveyors being pitched to convey snow toward the center of said plow, and said helical conveyors including flanges along the spiral extremities thereof, said flanges including edges directed inwardly toward the center of said plow, and in the conveying direction of said helical conveyors, means for reversing said fan to provide means for throwing snow to either desired side of said snow plow, means for driving said transverse helical conveyors including a central shaft to which said transverse helical conveyors are attached, and means drivingly connecting said forwardly positioned shaft and said conveyor shaft to simultaneously rotate the latter.

7. A snow plow comprising a cutting member including a substantially horizontal forwardly extending rotating shaft, a plurality of helically pitched blades attached to said shaft for rotation with the shaft, a plurality of cutting blades attached to and extending outwardly from the forward ends of said helically pitched blades, a fan

casing, a fan rotatably mounted in said casing, means for driving said fan and said cutting blades, and helical conveyors positioned transversely across said plow and positioned directly behind said cutting blades and below said helically pitched blades.

JOSEPH WANDSCHEER.
